UNITED STATES PATENT OFFICE.

HUBERT J. CAPELLMAN AND ROBERT HAYHURST, OF SOUTH CHICAGO, ILLINOIS.

POTATO-PEELING APPARATUS.

1,418,230.

Specification of Letters Patent. Patented May 30, 1922.

Application filed September 25, 1920, Serial No. 412,681. Renewed April 15, 1922. Serial No. 553,010.

To all whom it may concern:

Be it known that we, HUBERT J. CAPELLMAN and ROBERT HAYHURST, citizens of the United States, residing at South Chicago, 5 in the county of Cook and State of Illinois, have invented new and useful Improvements in Potato-Peeling Apparatus, of which the following is a specification.

This invention relates to a potato peeling 10 apparatus and has for its primary object the construction of an apparatus of this character that will peel potatoes in a clean manner and will not remove any of the eatable portion of the potato.

15 An object of the invention is to so act upon the skin of the potato that the same will be removed without disturbing the eatable portion of the potato.

Another object of the invention is to combine 20 in a single apparatus means for removing the skin from the potatoes and a device for removing the eyes of the potatoes.

A feature of our invention is that in the 25 rotation of the apparatus the potatoes will be acted upon for removing the skin.

With these and other objects in view the 30 invention will be better understood from the following detailed description taken in connection with the accompanying drawing

wherein:

Fig. 1 is a top plan view of the apparatus.

Fig. 2 is an end elevation.

Fig. 3 is a vertical sectional view.

Fig. 4 is a sectional view through the 35 receptacle.

Fig. 5 is a detailed sectional view.

Figs. 6 and 7 are detailed sectional views of the cutter.

Again referring to the drawing illustrating 40 one construction of our invention the numeral 1 designates a receptacle consisting of a cylinder 2, end plates 3 and 4. The cylinder consists of a body portion 5, and a cover 6 which forms substantially one-

45 half of the cylinder so that ready access may be had to the potatoes in the receptacle for removing the eyes in a manner hereinafter described. Each end plate is provided with a flange 7 to which the body

50 portion 5 is secured and to which the cover 6 is clamped by the thumb screws 8. It will be noted that the cover is provided with slots 9 so shaped that by giving a slight turn to the thumb nut the cover may be clamped

55 in place or may be allowed to be readily removed. It is, of course, understood any

other suitable clamping device may be used for holding the cover in place but the main purpose to be accomplished is to allow the cover to be quickly clamped and unclamped. 60

A stub shaft 10 is provided with spaced collars 11 and has the flange 12 secured to the end plate 4. A second stub shaft 13 has the flange 14 bolted to the end plate 3. This shaft 13 is provided with a bore 15 for 65 the purpose hereinafter described. The handle 16 is secured to the stub shaft 13 in any suitable manner.

The cover, body portion, and end plates have holes 17 punched therein in a manner 70 that numerous prongs 18 are formed having a cutting action upon the potatoes to remove the skin therefrom. One advantage of these holes, if found necessary, is that the receptacle may be partly submerged in 75 water so that during the removing of the skin the potatoes may be subject to a washing action.

The stub shafts are supported for rotation by the stand 19 of any suitable construction but shown in the drawings as formed from strap iron. As far as we have proceeded it will be seen that by depositing a number of potatoes in the body portion of the cylinder and then clamping the cover in position, rotation of the receptacle by the handle 16 will cause a rubbing action to take place between the potatoes and the prongs 18 with the result that the prongs will quickly and efficiently remove the skin from the potatoes. 90 To complete the operation it is necessary to remove the eyes from the potatoes and for this purpose we have shown a cutter 20 formed from the tube 21 of a size to rotate within the bore 15 and have one end formed 95 into a number of blades 22 disposed within the receptacle, so that the potato can be lifted and held in engagement with the blades so that upon rotation of the handle 23 the cutting edges 24 will remove the eyes. 100

From the foregoing description taken in connection with the accompanying drawing it will be apparent that we provide an apparatus of simple, inexpensive construction which will remove the skin in a clean manner and in an economical manner due to the fact that very little, if any, of the eatable portion of the potato is removed. 105

The novel manner of arranging the cutter with relation to the cylinder enables the 110 eyes to be quickly removed.

It is, of course, to be understood that the

invention may be constructed in various other manners and the parts associated in other relations and therefore, we do not desire to be limited in any manner except as set forth in the claims thereunto appended.

Having thus described our invention what we claim is:

1. A potato peeling apparatus comprising a receptacle having its interior surface shaped to have a cutting action with the potatoes, a cover for the receptacle, hollow stub shafts projecting from the receptacle, a stand for supporting the receptacle for rotation, a handle secured to one of the stub shafts, and a cutter mounted for rotation in one of the shafts with the knives thereof disposed within the receptacle for the purpose set forth.

2. In a potato peeling apparatus, a rotary receptacle, hollow stub shafts rotably supporting said receptacle, supports for said shafts, a cutter extending through one of said shafts and having the cutting edges thereof disposed within the receptacle, and a rotating handle on said cutter. 20 25

3. In a potato peeling apparatus, a cylindrical receptacle a handle for rotating said receptacle, and a potato eye removing cutter extending through said handle and having its cutting edges disposed within the receptacle. 30

In testimony whereof we affix our signatures.

HUBERT J. CAPELLMAN.
ROBERT HAYHURST.
